United States Patent [19]**Hayashi**[11] **Patent Number:** **Des. 394,904**[45] **Date of Patent:** ****Jun. 2, 1998****[54] CONTROL DEVICE FOR NON-CONTACT EYE PRESSURE MEASURING APPARATUS**D. 330,769 11/1992 Blaha et al. D24/172
3,564,907 2/1971 Holcomb et al. 600/405
5,474,066 12/1995 Grolman .... 600/383**[75] Inventor:** **Hideki Hayashi, Tokyo, Japan***Primary Examiner*—Stella Reid**[73] Assignee:** **Canon Kabushiki Kaisha, Tokyo, Japan***Attorney, Agent, or Firm*—Fitzpatrick, Cella, Harper & Scinto**[**] Term:** **14 Years****CLAIM****[21] Appl. No.:** **64,219**

The ornamental design for a control device for non-contact eye-pressure measuring apparatus, shown and described.

[22] Filed: **Dec. 24, 1996****DESCRIPTION****[30] Foreign Application Priority Data**

Jul. 9, 1996 [JP] Japan 8-20450

[51] LOC (6) Cl. ..... **24-01****[52] U.S. Cl.** ..... **D24/172****[58] Field of Search** D24/172; 600/398, 600/399, 400, 404, 405, 383

FIG. 1 is a front view of a control device for non-contact eye-pressure measuring apparatus showing my new design;

FIG. 2 is a rear view thereof;

FIG. 3 is a top plan view thereof;

FIG. 4 is a bottom plan view thereof;

FIG. 5 is a right side elevational view thereof, the opposite side elevational view being identical thereto; and,

FIG. 6 is a perspective view thereof.
